CONSTANT RESISTANCE AMPLIFIER
CIRCUITRene A. Braden, New York, N. Y., assignor to
Radio Corporation of America, a corporation
of Delaware

Application October 3, 1929, Serial No. 396,956

26 Claims. (Cl. 178—44)

My present invention relates to amplifiers, and, more particularly, to amplifying tuned circuits possessing either a constant effective resistance, or an effective resistance which is inversely proportional to frequency.

In band-pass tuned radio receivers employing a pair of coupled tuned circuits in each stage, it has been found necessary to insert resistance in the circuits to make the received band sufficiently uniform in amplification; that is to say, to make the amplifier amplify uniformly all band frequencies within the accepted band. This is necessary when the receiver is tuned to low wave frequencies, but is generally not necessary when the receiver is tuned to high wave frequencies for two essential reasons.

In the first place, the resistances of the coils in the tuned circuits are low at low wave frequencies, but increase rapidly with increasing wave frequencies. In the second place, considerably less total resistance is required in the tuned circuits at high wave frequencies than at low wave frequencies, if the band-pass circuits are such that a constant band width is accepted. It is desirable, therefore, to be able to add resistance in such a form that its magnitude is inversely proportional at any frequency to the frequency impressed upon the tuned circuits, so that the resistance of the circuit at each increasing frequency can be made to decrease as the frequency impressed upon the tuned circuits increases.

Again, in receivers employing a single tuned circuit in each stage, it is a common characteristic of such receivers to tune too sharply at low wave frequencies, and too broadly at high wave frequencies. In this case, it is helpful to add resistance to the tuned circuits at low frequencies to make them tune less sharply; but resistance should not be added at high frequencies.

In short, a variable-resistance element is required which will have high resistance at low frequencies, and low resistance at high frequencies, whereby the total effective resistance of the tuned circuit will be substantially the same, regardless of the impressed frequency.

Accordingly, it is one of the main objects of my present invention to employ, in a tuning circuit means for adding to the resistance of the tuned circuit an additional resistance which shall vary inversely with the impressed frequency, whereby the total circuit resistance can be made to either remain constant at all frequencies between two predetermined limits, or to decrease

as the frequency is varied from the lower limiting frequency to the upper frequency limit. For convenience in explanation, a tuned circuit which includes such means for adding a variable resistance will be called a constant resistance tuned circuit, it being understood that the name includes circuits adjusted to have highest resistance at the lowest frequency to which the circuit may be tuned, as well as circuits adjusted to have equal resistance at the highest and lowest frequencies to which the circuit may be tuned.

Another important object of the invention is to provide a multi-stage radio frequency amplifier which includes at least one tuned circuit in each pair of coupled input and output circuits, the tuned circuit possessing a constant resistance (according to the definition above) over a predetermined range of frequencies whereby the sharpness of tuning is substantially the same at all frequencies within the predetermined range.

Another object of the invention is to provide a band-pass amplifier including a series or chain of coupled circuits, at least two of which circuits are tuned, the tuned circuits possessing constant resistance (as defined above) over a predetermined range of frequencies whereby the band-pass amplifier amplifies uniformly all frequencies within the accepted band, each tuned circuit consisting of an inductance, a variable capacity, and a series impedance including a resistance and capacity in parallel.

Other objects of the invention are to improve generally the simplicity and efficiency of band-pass amplifiers, and to provide a tuned circuit which is reliable in operation, possesses constant resistance over a predetermined range of frequencies, and is economical to construct.

The novel features which I believe to be characteristic of my invention are set forth in particularity in the appended claims, the invention itself, however, as to both its organization and method of operation will best be understood by reference to the following description taken in connection with the drawings in which I have indicated diagrammatically several circuit organizations whereby my invention may be carried into effect.

In the drawings,

Fig. 1 shows a tuned circuit embodying one form of my invention,

Fig. 1A shows the electrical equivalent of the circuit in Fig. 1,

50

55

- Fig. 2 shows a tuned circuit employing a modified form of the invention,
 Fig. 3 is a graphic representation of the operation, as embodied in Fig. 1,
 5 Fig. 4 is a graphic representation of the operation, as embodied in Fig. 1,
 Fig. 5 is a graphic representation of the operation of the invention as shown in Fig. 2,
 Fig. 6 is a graphic showing of the operation of
 10 the invention as shown in Fig. 2,
 Fig. 7 is a graphic showing of the operation of the invention as shown in Fig. 2,
 Fig. 8 discloses a band-pass amplifier embodying the embodiment shown in Fig. 1,
 15 Fig. 9 discloses a tuned radio frequency amplifier incorporating the modification shown in Fig. 2,
 Fig. 10 is a graphic representation of the operation of the circuit shown in Fig. 9.

20 Referring to the accompanying drawings in which like characters of reference indicate the same parts in the different views, Fig. 1 shows a tuned circuit embodying the principle of my invention. This tuned circuit includes an inductance coil 1 which is electrically associated with the variable capacity 2, the two elements cooperating to tune the circuit to any desired frequency, there being inserted between the inductance and capacity a resistance R_0 in shunt with
 25 a capacity C_0 .

30 The circuit shown in Figure 1 is most readily explained by reference to the graphic representation in Figure 3, the latter disclosing the equivalent series impedance of the parallel resistance and capacity circuit. The impedance between the points a and b in Figure 1 is

$$Z' = \frac{1}{\frac{1}{R_0} + j\omega C_0} = \frac{R_0}{1 + \omega^2 R_0^2 C_0^2} - j \frac{R_0^2 \omega C_0}{1 + \omega^2 R_0^2 C_0^2} = R' + jX'$$

40 (where $\omega = 2\pi f$)

The circuit consisting of R_0 and C_0 in parallel is equivalent, therefore, to a resistance R' and
 45 a reactance X' in series as shown in Fig. 1A. The equivalent reactance, X' , necessitates a slight increase in the capacity of the variable condenser 2, to tune the circuit to a given frequency. The equivalent resistance, R' , adds directly to the
 50 resistance of the coil 1, R , making the total circuit resistance equal to $R+R'$, the condenser, 2, being assumed to have no resistance. Figure 3 represents graphically the ratio

$$\frac{Z'}{R_0}$$

55 this being given by diagonal lines from the origin to various points on the semicircle. The horizontal axis represents the ratio

$$\frac{R'}{R_0}$$

and the vertical axis represents the ratio

$$\frac{X'}{R_0}$$

70 Points on the circle represent the values of $\omega R_0 C_0$ ($= 2\pi f R_0 C_0$). If certain values of R_0 and C_0 are chosen, R' and X' are given by a point on the semi-circle in Fig. 3, and the variation of Z with frequency is indicated by the motion of the point around the semi-circle in the direction of the arrow. Figures around the semi-circle are
 75 proportional to frequencies.

It will be seen that if R_0 and C_0 are so selected that

$$\frac{Z'}{R_0}$$

5 at a certain frequency falls at the point a , (the resultant impedance ratio

$$\frac{Z'}{R_0}$$

10 being vectorially shown by the dotted line from zero to point a), then with increasing frequency, the value of R' is high and falls slowly while X' increases rapidly. Again, if

$$\frac{Z'}{R_0}$$

15 falls at the point b at a certain frequency, increasing frequency causes both R' and X' to decrease. If, as a third possibility,

$$\frac{Z'}{R_0}$$

20 falls at the point c at the middle of the semi-circle, X' is practically constant over a limited frequency range, and R' decreases as frequency increases.

25 If the principle embodied in Figs. 1 and 3 is to be employed in band-pass tuned radio receivers employing a pair of coupled tuned circuits in each stage, or in receivers employing a single tuned circuit in each stage, then a high ratio of maximum to minimum resistance is required and X' should fall in the region b , or between b and c , where although R' is much smaller than the
 30 resistance R_0 the range of variation of R' is very great, as will be readily perceived from the graphic representation in Fig. 3.

35 In Figure 4 there is graphically shown the total resistance of a tuned circuit, incorporating the
 40 impedance R_0 , C_0 in series, calculated for a coil whose inductance was 306 microhenries and whose resistance was found by actual measurement to be as shown by curve K in Figure 4. In curves A, B, and C, $\omega R_0 C_0$ was equal to 3
 45 at a frequency of 600 kilocycles, and had proportional values at other frequencies. R_0 was equal to 50, 100, and 150 ohms respectively, in the three curves, and C_0 to .0159, .00795, and .0053 microfarads, respectively. Curves D, E,
 50 and F were calculated for values of R_0 of 25, 50 and 100 ohms, respectively, and of C_0 of .0212, .01106 and .0053 microfarads, respectively. At 600 kilocycles, $\omega R_0 C_0$ was equal to 2. Curves G, H, I, and J were calculated for values of R_0
 55 of 10, 20, 30, and 40 ohms, respectively, and of C_0 of .0265, .01325, .00885, and .006625 microfarads, respectively, and at 600 kilocycles, $\omega R_0 C_0$ was equal to 1.

60 Curve J represents a circuit in which the impedance $C_0 R_0$ has been adjusted for higher total circuit resistance at 600 kilocycles than at 1500 kilocycles, while Curve I represents a circuit in which C_0 , R_0 has been adjusted for equal total circuit resistances at the two limiting frequencies, 65 600 and 1500 kilocycles. All of the curves (except curve K) fall within the scope of the invention, since they differ only in the degree to which the resistance-correcting means is applied.

70 In Fig. 2, I have shown a modified embodiment of my invention, this form including the tuned circuit consisting of the inductance coil 1 and the variable capacity 2. An impedance net-work is inserted in series with the inductance 1 and capacity 2, the net-work consisting of an inductance
 75

L_0 in series with a resistance R_L , the inductance and resistance being in shunt with a series connection of a capacity C_0 and resistance R_c . The impedance of the circuit L_0 , R_L , C_0 and R_c in Fig. 2 varies as shown by curves A and B in Fig. 5.

This figure graphically shows the aforesaid relationship between impedance and frequency, the horizontal axis denoting frequencies and the vertical axis denoting impedance. With increasing frequency, R' first increases and then decreases. For the applications described in the foregoing paragraph the descending part of the curve would be used, the constants being so chosen that at the lowest frequencies to be received, R' would be, say, at the point a , and at the highest frequency would be at the point b . By suitable choice of the circuit constants the resistance R' can be made to have any two selected values of resistance at two selected frequencies.

In Figure 6, there is graphically shown the resistance and reactance at various frequencies, of a circuit consisting of L_0 , R_L , C_0 , and R_c , arranged as in Figure 2. The constants of this circuit were as follows: $L_0=7 \times 10^{-6}$ henries, $R_L=40$ ohms, $C_0=0.66 \times 10^{-8}$ farads, and $R_c=0$. As an example of the interpretation of the curves in Figure 6, take the frequency $2\pi f=7 \times 10^6$. At this frequency the circuit is exactly equivalent to a resistance of 8 ohms in series with a condenser having a reactance of 27 ohms, which is found by calculation to be a condenser of $.529 \times 10^{-8}$ farads capacity. R' is therefore equal to 8, and X' to -27. Values of R' and X' for other frequencies are given by the solid line curves in Figure 6. The curves in dotted lines give the typical variation of R' and X' when R_L and R_c are small.

In Figure 7, curve K shows the radio frequency resistance of the coil used for Figure 4. Curve M is a portion of the R' curve in Figure 6. Curve O shows the total resistance, $R+R'$, of the coil and the resistance-correcting circuit in series. Curve L gives the equivalent resistance R' of a different resistance-correcting network, and curve N is the resistance of the complete circuit. Curve P shows the same thing, $R+R'$, for still another resistance-correcting circuit, having the constants $L_0=1.75 \times 10^{-6}$ henries, $R_L=10$ ohms, $C_0=2.64 \times 10^{-8}$ farads, and $R_c=0$.

In Fig. 8, I have shown an amplifying circuit of the band-pass type employing the embodiment shown in Fig. 1. The incoming signal energy is impressed across the input terminals of a screen grid tube 1', the output circuit of the tube being tuned by the variable capacity 2 and the inductance coil 1, the coil 1, being coupled as at M to the coil 6, in the input circuit of the succeeding screen grid tube 9. The input circuit of the tube 9 is tuned by the variable capacity 5, and the amplified output of the tube 9 is impressed upon a succeeding stage and utilized in any well-known fashion.

In the tuned output circuit of tube 1' and the tuned input circuit of the tube 9, there are connected the impedance circuits in series with the variable capacity and inductance coil in each tuning circuit. This impedance circuit as shown in Fig. 1, consists of a resistance R_0 in shunt with a capacity C_0 . As explained heretofore this arrangement will result in a uniform amplification of all frequencies within the accepted band.

In Fig. 9 there is shown a tuned radio frequency amplifier circuit which incorporates the

modification as shown in Fig. 2. Here, again, the incoming signal energy is impressed across the input circuit of the triode 10, the output circuit of the latter including an inductance coil 11 which is inductively coupled, as at M, to the coil 5 in the input circuit of the triode 12. The input circuit of the triode 12 is tuned by a variable capacity 2, there being an impedance circuit in series with the inductance coil 1 and the variable capacity 2. The impedance circuit, as shown in Fig. 2, consists of the inductance L_0 in series with the resistance R_L , the latter two elements being in shunt with the series connection between the capacity C_0 and resistance R_c .

A series of resonance curves of an amplifying circuit of the type shown in Fig. 9 are shown in Fig. 10. Curve A shows the characteristic of the resonance curve at 1400 kilocycles with, and without, the extra impedance elements inserted in the tuned input circuit of the tube 12, the dotted curve representing the characteristic with the impedance elements inserted, while the solid line curve represents the characteristic without the impedance elements included in the tuned input circuit.

Curve B represents the same state of affairs at 1000 kilocycles, while curve C indicates a similar state of affairs at 600 kilocycles. It will be observed that as the frequencies impressed decrease, the function of the impedance elements is more sharply defined. It is believed that Fig. 10 illustrates very clearly the advantage to be derived from including impedance elements, according to my novel principles, in the tuned circuit of the amplifier, the dotted lines indicating that a substantially constant degree of sharpness of tuning is secured throughout a predetermined range of frequencies. This is shown by the fact that the three dotted curves are substantially the same in shape, and equally wide across the base of the curves.

While I have indicated and described several systems for carrying my invention into effect, it will be apparent to one skilled in the art that my invention is by no means limited to the particular organizations shown and described, but that many modifications in the circuit arrangements, as well as in the apparatus employed, may be made without departing from the scope of my invention as set forth in the appended claims.

What I claim is:

1. A constant resistance tuned circuit consisting of the combination in series of an inductance coil, a condenser and a parallel branch network, the network having resistance and inductance in series in one branch, and resistance and capacity in series in the other branch.

2. A multi-stage radio frequency amplifier having coupled tuned circuits in each stage and means including resistance in at least one of said circuits for establishing a constant resistance characteristic whereby with constant accepted band width the amplification over the range of the accepted band is maintained uniform, at any midband frequency.

3. A multi-stage tuned radio frequency amplifier comprising a chain of coupled circuits, at least one of said circuits being tuned, an impedance network in said tuned circuit, said net work including a resistance in shunt with a capacity, the electrical constants of the net-work elements being so proportioned that the magnitude of the effective resistance of said net-work is inversely proportional to the frequency to which the amplifier is tuned.

4. A multi-stage amplifier comprising a pair of coupled circuits at least one of said circuits being tuned, and means, including a plurality of reactances, in the tuned circuits for establishing 5 a constant resistance characteristic whereby with constant accepted band width the amplification over the range of the accepted band is maintained uniform, at any mid-band frequency.

5. A multi-stage radio frequency amplifier having 10 coupled tuned circuits in each stage, and means, including a series impedance path, in one of the tuned circuits for establishing a constant resistance characteristic whereby with constant accepted band width the amplification over 15 the range of the accepted band is maintained uniform, at any mid-band frequency.

6. In an amplifier, as defined in claim 5, said series impedance path containing resistance and capacity in parallel.

20 7. A multi-stage radio frequency amplifier, as defined in claim 2, said resistance being connected in parallel with a capacity.

8. A multi-stage radio frequency amplifier including 25 at least one tuned circuit provided with a variable tuning condenser in each pair of coupled input and output circuits, and an impedance path in said tuned circuit whose reactance and resistance is proportioned so that the circuit has a constant resistance characteristic over a predetermined range of frequencies whereby the sharpness of tuning is substantially the same at all frequencies within the predetermined range.

9. A band pass amplifier including a chain of 35 coupled circuits, at least two of which circuits are tuned, the tuned circuits possessing constant resistance over a predetermined range of frequencies whereby the band pass amplifier amplifies uniformly all frequencies within the accepted band, each tuned circuit consisting of an inductance, a variable capacity, and a series impedance including at least a resistance and capacity in parallel.

10. A network, adapted to transmit a band of 40 super-audible frequencies of substantially constant width over a tuning range with substantial uniformity, comprising a pair of coupled oscillatory circuits each including an inductance and capacity, means for varying the resonant frequency of said circuits to tune the network over 45 said range, and an impedance path in series with the inductance and capacity in each of said circuits, said path including reactance and resistance of such magnitude that the over-all resistance of said network decreases as the network 50 is tuned to the high frequency end of said range.

11. A super-audible frequency transmission 55 network comprising an oscillation circuit consisting of an inductance element and a shunt capacity element, said capacity element being adjustable in magnitude to vary the resonant frequency of the circuit over a range of frequencies, said circuit additionally including an impedance path in series with said elements whose reactance and resistance is so proportioned that the resistance of said path decreases in a predetermined manner as the frequency of the circuit is adjusted to the high frequency end of said range.

12. A super-audible frequency transmission 60 network comprising an oscillation circuit consisting of an inductance element and a shunt capacity element, said capacity element being adjustable in magnitude to vary the resonant frequency of the circuit over a range of frequencies, 70 said circuit additionally including a series im-

pedance path whose reactance and resistance is so proportioned that the total effective resistance of the circuit remains substantially constant over said range whereby a substantially constant degree of sharpness of tuning of said circuit is 5 secured throughout said range.

13. In combination with a source of radio frequency energy and an electron discharge tube, a network comprising an oscillatory circuit connected to said source and a second oscillatory 10 circuit connected between the input electrodes of said tube, said circuits being coupled to transfer energy from said source to said tube, means for tuning at least one of the circuits through a frequency range, and an impedance in said 15 last circuit whose reactance and resistance is so proportioned that the total effective resistance of the circuit remains substantially constant over said range whereby a substantially constant degree of sharpness of tuning thereof is secured 20 throughout said range.

14. In combination, a pair of cascaded tubes, a coupling network between the tubes comprising at least two coupled oscillation circuits each including an inductance coil and a condenser, said 25 both circuits being resonant to the same frequency, and a lumped impedance connected in series with the condenser of each circuit, said impedances comprising reactance and resistance so chosen that the effective resistance of the 30 network varies inversely with frequency.

15. In combination, a pair of cascaded tubes, a coupling network between the tubes comprising at least two coupled oscillation circuits each including an inductance coil and a variable condenser, said both circuits being resonant to the 35 same frequency, and a lumped impedance connected in series with the condenser and coil of each circuit, said impedances comprising reactance and resistance so chosen that the effective resistance of the network varies inversely with frequency.

16. In a tunable band pass network of the type comprising a pair of reactively coupled resonant oscillation circuits, said network being adapted 45 to transmit a band of frequencies consisting of the modulation frequencies of a modulated carrier, means for tuning said circuits to common carrier frequencies of a desired carrier frequency range, an electron discharge tube load coupled 50 to said network, an impedance device in at least one of said circuits whose resistance varies inversely with carrier frequency in such a manner that all the modulation frequencies of any carrier frequency selected from said range are transmitted through said network to said load with 55 substantial uniformity.

17. In combination with an electron discharge tube, a resonant oscillation circuit, adapted to have modulated radio frequency currents of a desired frequency range impressed thereon, said circuit consisting of a coil, a variable tuning condenser to tune it through said range, and an impedance device whose resistance automatically decreases as the circuit is tuned to the high frequency end of said range and currents of increasing frequency are impressed on said circuit.

18. In combination with an electron discharge tube, a resonant oscillation circuit, adapted to have modulated radio frequency currents of a desired frequency range impressed thereon, said circuit consisting of a coil, a variable tuning condenser to tune it through said range, and an impedance device whose resistance automatically decreases in such a manner as the circuit is tuned 75

- to the high frequency end of said range and currents of increasing frequency are impressed on said circuit that said circuit is provided with a constant selectivity characteristic.
- 5 19. A high frequency electrical coupling system including at least one resonant circuit tunable throughout a frequency range, and fixed impedance means included in said resonant circuit producing effects so variable with frequency as 10 to provide approximately the same resonance band widths for said coupling system at the upper and lower frequency limits of said tunable range.
20. A high frequency electrical coupling system including at least one resonant circuit tunable throughout a frequency range, and fixed impedance means included in said resonant circuit producing effects so variable with frequency as 15 to minimize changes in selectivity of said coupling system as the tuning is adjusted throughout said frequency range.
21. A high frequency electrical coupling system including at least one resonant circuit tunable throughout a frequency range, and energy dissipating impedance means decreasing in dissipative effect with increase in frequency included in said resonant circuit for reducing variations in selectivity of said coupling system throughout said tunable range.
- 25 22. A high frequency electrical coupling system including at least one resonant circuit tunable throughout a frequency range, and fixed impedance means comprising resistance shunted by 20 capacity serially interposed in said resonant circuit for reducing variations in selectivity of said 25 capacity.
26. A high frequency electrical coupling system tunable throughout a range in frequency, 25 adapted to interconnect successive portions of a multi-stage amplifier, said system comprising a primary circuit and a tunable resonant secondary circuit inductively coupled to said primary circuit and means associated with said secondary 30 circuit for introducing losses therein which vary as said circuit is tuned throughout said range to maintain substantially constant the selectivity of said system throughout said tunable frequency range.
